HEAT ACCUMULATOR

Anne Escher, The Hague, Netherlands

Application August 1, 1947, Serial No. 765,544
In the Netherlands May 9, 1945Section 1, Public Law 690, August 8, 1946
Patent expires May 9, 1965

9 Claims. (Cl. 110—97)

1

The invention relates to a heat accumulator which serves to store and to retain temporarily the heat developed by one or more sources of heat in order to be able to deliver or withdraw it at any desired moment.

This result is obtained by the heat accumulator according to the invention by the fact that it comprises at least one source of heat, at least one device or place for taking off heat, and a heat holding mass or body provided with passages through which a fluid heated by the source of heat flows by thermosyphon action, optionally increased or intensified by positively driven means.

As a source of heat any arbitrary type of furnace may be used, but it is also possible, for example, to use a source of heat which involves one or more channels through which combustion gases or other hot gases or fluids are caused to flow. The device for withdrawing the heat may comprise a boiler, a superheater, an economiser, furnace means, cooking pans, etc.

A special advantage of the heat accumulator according to the invention is that the heat may be withdrawn from it at any desired moment and in any desired way. Hence, it may be used for various purposes, and furthermore it is particularly suitable to supply the larger quantity of heat required at peak hours, without it being necessary then for the source of heat at that moment to furnish a larger quantity of heat, with the result that the source of heat may keep functioning in an economical way. The larger quantity of heat to be given off to the device or place for withdrawing it is then obtained by making the fluid in the heat accumulator circulate more rapidly which may be effected by further opening one or a number of valves.

The heat holding mass or body provided with passages may consist of any arbitrary material which can absorb and deliver heat, for example, stone, metal, etc. As passages in the heat holding body or mass, channels may be used in such a number and to such extent that the mass is riddled. However, larger spaces may also be disposed in the mentioned body or mass. In any case it will be arranged that the fluid meets with as small a resistance as possible when it flows through the heat accumulator. The passages or channels may be provided in a simple manner by composing the mass of stones or blocks which are stacked with interspaces so that perforate walls are formed. Said walls may also comprise cast plates which are formed with holes or channels. In a preferred embodiment of the heat accumulator

2

according to the invention, the walls or plates are placed in such position that they run parallel to the flow of the fluid caused by the thermosyphon action. The holes or channels in the walls or plates may be disposed somewhat inclined according to the invention whereby the fluid flows therethrough more easily on heating.

According to the invention the source of heat may be separated from the passage riddled mass or body in such manner that the same fluid constantly flows and is at least partly recirculated in the passages of said mass. The source of heat, however, may also be in open communication with the perforate body or mass whereby part of a heat transmitting fluid in the latter will be replaced each time by a quantity of fluid thus from the source of heat, so that the fluid flows several times through the passages in the heat holding body or mass and is progressively discharged from said passages, for example to a chimney.

According to the invention one or a number of adjustable or self-adjusting control members are preferably disposed in the connection between the source of heat and the mentioned body or mass. Thus, the number of times that the same quantity of fluid circulates in the body or mass may be controlled, and it is also possible to close one or more control members so that in certain sections of the heat accumulator a renewal of the fluid does not occur.

According to the invention the distance between the control members may decrease in a furnace towards the back, and/or the size of said control members may also increase rearwardly. Thus, not only may the temperature of the furnace be controlled, but at the same time the length of the furnace may be adjusted.

A preferred embodiment of the heat accumulator according to the invention is characterized in that the perforate heat holding body or mass is divided into compartments by one or a number of closed walls or plates. This makes it possible to cause fluids of various temperatures to circulate in the various compartments so that the hottest portions of the source of heat impart their heat to compartments in which the fluid has a higher temperature than in compartments which are heated by a colder portion of the source of heat. Some compartments may also be in open communication with the source of heat, while other compartments are not.

According to the invention the devices for withdrawing heat may be housed in separate compartments, providing the advantage that said devices may be put into action in part, so that no portions are heated unnecessarily.

For effecting the control of a battery of boilers of an electric power station, according to the invention the control members for this purpose may be adjusted automatically in dependence upon the steam pressure and/or the intensity of current in the electric circuit, so that compartments may be switched in or out, and the flow rates for the fluid in said compartments may be controlled.

The drawing represents by way of example an embodiment of the heat accumulator made according to the invention.

Figure 1 is a cross section.

Figure 2 is a section along the line II-II of Figure 1.

The heat accumulator represented in the drawing comprises a longitudinal fire box type furnace 1 disposed in a space which is filled with a heat holding body or mass for absorbing and delivering heat. Said body or mass is formed in this accumulator by walls composed of stones with interspaces or by spaced plates 2 provided with holes or channels. The walls or plates run parallel to the flow of the fluid caused by the thermosyphon action. The holes in the walls or plates 2 are preferably disposed in somewhat inclined positions with respect to the horizon.

The wall of the furnace has a first and a second longitudinal zone and is provided in said second zone with a number of openings which are equipped with valves 3 which may be opened and closed either automatically or otherwise, and which are disposed in staggered relationship on one side of the furnace with regard to the valves being present on the other side. The distance of the valves decreases towards the back. Below the furnace there is a conveyor 4 for the ash arranged in a channel 4a which latter is provided with transversally extending partition walls 4b.

The space filled with the mass taking up and giving off heat is covered by an insulating wall 5 which is provided at the upper edge with an aperture 6 which may be closed with a valve 7 when no heat is taken off. In order to obtain a rate of flow of the fluid which is as uniform as possible in all the passages and portions of the passages, a recess 16 is disposed in the body or mass 2 in the neighbourhood of the aperture 6. As the air or the gas in the accumulator is heated by the furnace 1 it will move upwards. If the valves 15 or the valve 7 are, or is closed, said heated air cannot move into the channel 9, so that it will move downwards through holes provided in a colder part of the accumulator towards the furnace 1, where it is again heated. As the accumulator shown in Figure 1 is symmetrical, the gases will circulate in each half of the accumulator. It is, however, of no importance to obtain a perfectly symmetrical gas circulation.

The whole accumulator is surrounded by an outer wall 8 in such a way that between the wall 5 and said outer wall 8 a channel 9 is provided. In said channel a tube boiler 10, a superheater 11, a second tube boiler 12 and an economiser 13 are disposed. The economiser, however, may also be placed in the chimney 14, and then hot water may be stored.

In the channel 9 there is arranged a valve 15 with which the speed of circulation of the fluid may be controlled.

The above-described device works as follows:

When the fire in the fire box 1 is started the fluid medium in the structure surrounding the fire box will be caused to circulate. Such fluid

medium will be constituted by the air filling the spaces in the heat accumulator 2. In the rear part of the furnace where the openings 3 are located the fluid medium will be formed also by the combustion gases when the valves for the openings are open.

When the opening 16 is closed by the closure member 7 the air or combustion gas or mixture thereof will circulate in a closed circle in each half of the heat accumulator as indicated in the left hand section by the arrow A. As soon as the closure member 7 is lifted, the circulation will take place not only through the heat accumulator, but also through the surrounding passage 9 as indicated by the dotted line arrow B.

In addition, in the rear portion of the furnace where communication is provided between the fire box and the heat accumulator by means of the adjustable openings 3, the hot combustion gases will enter the heat accumulator and will displace part of the air and gases therefrom into the chimney 14 as indicated by the arrow C. The speed of circulation may be controlled by the valve 15. The furnace 1 keeps giving off its heat to the heat holding body mass, and according to the magnitude of the speed of the fluid in the channel 9 the first described circulation will become more rapid or slower.

During the functioning of the furnace the valves 3 may be opened more or less. Thereby combustion gases will flow into the passages so that part of the fluid after circulating several times through the heat accumulator will escape into the atmosphere via the chimney 14.

I claim:

1. A furnace assembly, including the combination of a wall forming a longitudinal fire box having a first and a second longitudinal zone therein; a heat accumulator disposed adjacent to said fire box and provided with a plurality of channels formed in said heat accumulator; said wall having openings in said second zone of said fire box for providing a communication between said second zone of said fire box and the adjoining channels of said heat accumulator; wall means forming an outer furnace shell, spaced from said heat accumulator so as to form an intermediate passage encircling the major part of said heat accumulator; an insulating covering disposed on the exterior of said heat accumulator; container means for the fluid to be heated located in said intermediate passage; the insulating covering having top and bottom openings adjacent the top portion and bottom portion of said heat accumulator; and operative closure means for closing at least one of said openings so that the heated fluid circulates by thermosiphon action through the channels of said heat accumulator in closed position of said closure means and circulates by thermosiphon action through said channels of said heat accumulator and through said intermediate passage in open position of said closure means.

2. A furnace assembly including the combination of a wall forming a longitudinal fire box having a first and a second longitudinal zone therein; a heat accumulator disposed adjacent to said fire box and provided with a plurality of channels formed in said heat accumulator; said wall having openings in said second zone of said fire box and the adjoining channels of said heat accumulator; valve means for controlling said openings; wall means forming an outer furnace shell spaced from said heat accumulator so as

5

to form an intermediate passage encircling the major part of said heat accumulator; an insulating covering disposed on the exterior of said heat accumulator; container means for the fluid to be heated located in said intermediate passage; the insulating covering having top and bottom openings adjacent the top portion and bottom portion of said heat accumulator; and operable closure means for closing at least one of said openings so that the heated fluid circulates by thermosiphon action through the channels of said heat accumulator in closed position of said closure means and circulates by thermosiphon action through said channels of said heat accumulator and through said intermediate passage in open position said closure means.

3. A furnace assembly including the combination of a wall forming a longitudinal fire box having a first and second longitudinal zone therein; a source of heat disposed in said first zone of said fire box; a heat accumulator disposed adjacent to said fire box and provided with a plurality of channels formed in said heat accumulator; said wall having openings in said second zone of said fire box for providing a communication with the adjoining channels of said heat accumulator, the spacing of the said openings decreasing in a direction remote from said source of heat; wall means forming an outer furnace shell spaced from said heat accumulator so as to form an intermediate passage encircling the major part of said heat accumulator; an insulating covering disposed on the exterior of said heat accumulator; container means for the fluid to be heated disposed in said intermediate passage; said insulating covering having top and bottom openings adjacent the top portion and bottom portion of said heat accumulator; operable closure means for closing at least one of said openings so that the heated fluid circulates by thermosiphon action through the channels of said heat accumulator in closed position of said closure means and circulates by thermosiphon action through said channels of said heat accumulator and through said intermediate passage in open position of said closure means.

4. A furnace assembly including the combination of a wall forming a longitudinal fire box having a first and a second longitudinal zone therein; a source of heat disposed in said first zone of said fire box; a heat accumulator disposed adjacent to said fire box and provided with a plurality of channels formed in said heat accumulator; said wall having openings in said second zone of said fire box for providing a communication with the adjoining channels of said heat accumulator, the spacing of the said openings decreasing in a direction remote from said source of heat; valve means for controlling said openings; wall means forming an outer furnace shell spaced from said heat accumulator so as to form an intermediate passage encircling the major part of said heat accumulator; an insulating covering disposed on the exterior of said heat accumulator; container means for the fluid to be heated located in said intermediate passage; said insulating covering having top and bottom openings adjacent the top portion and bottom portion of said heat accumulator; and operable closure means for closing at least one of said openings so that the heated fluid circulates by thermosiphon action through the channels of said heat accumulator and through said intermediate passage in open position of said closure means.

6

5. A furnace assembly comprising in combination, a longitudinally extending wall forming an elongated fire box; a source of heat located within said wall at one end of said fire box; a heat accumulator located adjacent to said fire box and provided with a plurality of channels; wall means forming an outer furnace shell spaced from said heat accumulator so as to form an intermediate passage encircling at least part of said heat accumulator; a covering disposed on the exterior of said heat accumulator having openings adjacent to the top and bottom portions of said heat accumulator, at least one opening communicating with said intermediate passage; container means for the fluid to be heated located in said intermediate passage; and operable closure means for closing at least one of said openings so that the heated fluid circulates by thermosiphon action through the channels of said heat accumulator in closed position of said closure means and circulates by thermosiphon action through said channels of said heat accumulator and through said intermediate passage in open position said closure means.

6. A furnace assembly comprising in combination, a longitudinally extending wall forming an elongated fire box; a source of heat located within said wall at one end of said fire box; a heat accumulator located adjacent to said fire box and provided with a plurality of channels, a portion of said wall spaced from said source of heat being formed with openings for providing a communication between said fire box and the adjoining channels of said heat accumulator; wall means forming an outer furnace shell spaced from said heat accumulator so as to form an intermediate passage encircling at least part of said heat accumulator; a covering disposed on the exterior of said heat accumulator having openings adjacent to the top and bottom portions of said heat accumulator, at least one opening communicating with said intermediate passage; container means for the fluid to be heated located in said intermediate passage; and operable closure means for closing at least one of said openings so that the heated fluid circulates by thermosiphon action through the channels of said heat accumulator in closed position of said closure means and circulates by thermosiphon action through said channels of said heat accumulator and through said intermediate passage in open position said closure means.

7. A furnace assembly comprising in combination, a longitudinally extending wall forming an elongated fire box; a source of heat located within said wall at one end of said fire box; a heat accumulator located adjacent to said fire box and provided with a plurality of channels, a portion of said wall spaced from said source of heat being formed with openings for providing a communication between said fire box and the adjoining channels of said heat accumulator; valve means for controlling said openings in said portion of said wall; wall means forming an outer furnace shell spaced from said heat accumulator so as to form an intermediate passage encircling at least part of said heat accumulator; a covering disposed on the exterior of said heat accumulator having openings adjacent to the top and bottom portions of said heat accumulator, at least one opening communicating with said intermediate passage; container means for the fluid to be heated located in said intermediate passage; and operable closure means for closing at least one of said openings so that

the heated fluid circulates by thermosiphon action through the channels of said heat accumulator in closed position of said closure means and circulates by thermosiphon action through said channels of said heat accumulator and through said intermediate passage in open position said closure means.

8. A furnace assembly, comprising in combination, a longitudinally extending wall forming an elongated fire box; a source of heat located within said wall at one end of said fire box; a heat accumulator located adjacent to said fire box and provided with a plurality of channels, a portion of said wall spaced from said source of heat being formed with openings for providing a communication between said fire box and the adjoining channels of said heat accumulator, the spacing of said openings decreasing in a direction towards the other end of said fire box; valve means for controlling said openings in said portion of said wall; wall means forming an outer furnace shell spaced from said heat accumulator so as to form an intermediate passage encircling at least part of said heat accumulator; a covering disposed on the exterior of said heat accumulator having openings adjacent to the top and bottom portions of said heat accumulator, at least one opening communicating with said intermediate passage; container means for the fluid to be heated located in said intermediate passage; and operable closure means for closing at least one of said openings so that the heated fluid circulates by thermosiphon action through the channels of said heat accumulator in closed position of said closure means and circulates by thermosiphon action through channels of said heat accumulator and through said intermediate passage in open position said closure means.

9. A furnace assembly, comprising in combination, a longitudinally extending wall forming an elongated fire box; a source of heat located within said wall at one end of said fire box; a heat accumulator located adjacent to said fire box and provided with a plurality of channels, said heat accumulator body including a plurality of transversely extending members defining a plurality of transversely extending compartments,
